(57) **CLAIM**

The ornamental design for a mid sectional gatherable bag, as shown and described.

DESCRIPTION

FIG. 1 is a front elevational view of the first embodiment of a mid sectional gatherable bag in an uncompressed state, the rear elevational view being a mirror image thereof.

FIG. 2 is a left side perspective view of FIG. 1, the right side perspective view being a mirror image thereof.

FIG. 3 is a top front perspective view of FIG. 1

FIG. 4 is a bottom rear perspective view of FIG. 1

FIG. 5 is a front elevational view of the first embodiment of a mid sectional gatherable bag compressed at the center of the bag, the rear elevational view being a mirror image thereof.

FIG. 6 is a left side perspective view of a FIG. 5, the right side perspective view being a mirror image thereof.

FIG. 7 is a top front perspective view of FIG. 5

FIG. 8 is a bottom perspective view of FIG. 5

FIG. 9 is a front elevational view of the first embodiment of a mid sectional gatherable bag compressed at the center of the bag and at the sides, the rear elevational view being a mirror image thereof.

FIG. 10 is a left side perspective view of a FIG. 9, the right side perspective view being a mirror image thereof.

FIG. 11 is a top front perspective view of FIG. 9

FIG. 12 is a bottom rear perspective view of FIG. 9

FIG. 13 is a front elevational view of the second embodiment of a mid sectional gatherable bag in an uncompressed state, the rear elevational view being a mirror image thereof.

FIG. 14 is a top front perspective view of FIG. 13

FIG. 15 is a bottom rear perspective view of FIG. 13

FIG. 16 is a front elevational view of the second embodiment of a mid sectional gatherable bag compressed at the center of the bag, the rear elevational view being a mirror image thereof

FIG. 17 is a top front perspective view of FIG. 16

FIG. 18 is a bottom rear perspective view of FIG. 16

FIG. 19 is a front elevational view of the second embodiment of a mid sectional gatherable bag compressed at the center of the bag and at the sides, the rear elevational view being a mirror image thereof.

FIG. 20 is a top front perspective view of FIG. 19; and,

FIG. 21 is a bottom rear perspective view of FIG. 19.

The broken lines showing the webbing, and stitching are to show environment only and are not part of the claimed design.
